UNITED STATES PATENT OFFICE.

JOHN BARCLAY, OF TORONTO, ONTARIO, CANADA.

MACHINE FOR DRYING GRAIN.

SPECIFICATION forming part of Letters Patent No. 254,903, dated March 14, 1882.

Application filed December 15, 1881. (No model.)

To all whom it may concern:

Be it known that I, JOHN BARCLAY, a subject of the Queen of Great Britain, residing at the city of Toronto, in the county of York, in 5 the Province of Ontario, Canada, have invented a certain new and useful Machine for Drying Oats and other Grain, of which the following is a specification.

The object of the invention is to provide an apparatus by which oats and other grain may 10 be dried by the direct application of the heat from the fire without being injuriously affected by the smoke ascending therefrom, and also in having the apparatus so arranged that the 15 grain may be thoroughly dried while passing through it, without requiring any manual labor from the time it enters the machine till it is discharged therefrom.

In the drawings, Figure 1 is a longitudinal 20 section of my improved drying-machine. Fig. 2 is a cross-section thereof through *x y*, and Fig. 3 is a detail view of the sieve.

A is an outer casing, preferably made of 25 brick, which may be constructed of iron or other suitable material.

B is a furnace built within the casing A.

C is an air-space formed on one end of the 30 casing A, behind the furnace, and extending upwardly to the top of the casing.

D are pipes leading from the air-space C, 35 through the furnace and into the air-space E, formed between the bottom F and sieve G. In the drawings two riddles constructed in this manner are shown in the machine; but it will of course be understood that more riddles 40 may be supplied, if thought desirable.

B' are openings provided with dampers and arranged to admit the smoke from the furnace 45 into the space under, over, and between the sieves, as indicated by arrows, the smoke finally escaping through the chimney H.

I is a pressure-fan arranged to force air into 50 the air-space C, and thence through the air-pipes D into the air-spaces E, where it escapes through the sieves G, and finally, mixing with the smoke, escapes through the chimney H.

J is a hopper-shaped spout through which 55 the grain is introduced onto the top sieve, G. This sieve inclines slightly from the bottom of the spout J. Consequently the grain admitted

thereto spreads over it till it reaches its end, when it falls over onto the sieve below it, which is slanted in the reverse direction, the grain being thus spread over its surface till its other end is reached, when it falls through into the 55 spout K, which carries it to the outside of the casing. As I have before said, more sieves may be introduced, if desired. In order to assist the grain to travel along the face of the sieves, I provide means for agitating or shaking the said sieves. This may be effected in various ways. The plan I adopt is to place a vertical shaft, L, at one end of the casing A, and provide the said shaft with wipers M, arranged to come in contact with brackets N 60 fixed to the end of the riddles, as shown. The vertical shaft L is caused to revolve by suitable means, imparting thereby the required agitation to the riddles through the wipers M coming in contact with the brackets N and 65 70 forcing the riddles in one direction, the said riddles being carried back by the action of a spring, thereby causing a jerking movement to the riddles which produces the desired effect upon the grain.

Although the smoke, as before stated, is admitted into the space immediately over the grain, it cannot come in contact therewith, as the pressure of the heated air escaping through the perforations in the sieve G prevents so undesirable a result, while the heat from the smoke is fully utilized for the purpose of assisting in drying the grain.

Dampers O are provided for the smoke-flues leading from the furnace. In this manner the 85 fire is checked, and also the amount of smoke admitted into the casing is regulated thereby.

I do not in this application broadly claim the application of heated air and products of combustion, in the manner described, to grain-receptacles, as I have claimed such invention in a separate application of even date herewith.

What I claim as my invention is—

1. In a machine for drying oats and other grain through the application of artificial heat, 95 one or more sieves arranged to carry the grain, and contained within a chamber through which the smoke and heated gases from a furnace are conducted, an air-space below each sieve and supplied with heated air under pressure, 100

so that in passing through the sieves the force of its escape prevents the smoke mixing with the grain carried on the sieves.

2. The sieves G, provided with air-chambers 5 E, in combination with the furnace B, the pipes D, passing through the furnace and into the air-chambers E, and suitable means for forcing a current of air through said pipes D, substantially as described.

10 3. The combination, with the sliding sieves

G, of springs at one end of said sieves, and the vertical shaft L, provided with wipers M, to operate against the opposite ends of said sieves, and the pipes D, serving as inlets to the sieves and as supports for the said springs, 15 substantially as described.

JOHN BARCLAY.
